Primary Examiner—Stella Reid*Assistant Examiner*—E. Watterson*Attorney, Agent, or Firm*—Marshall, O'Toole, Gerstein, Murray & Borun**[57] CLAIM**

The ornamental design for a valve actuator, as shown and described.

DESCRIPTION

FIG. 1 is a perspective view taken from above and to the left of a valve actuator showing our new design;

FIG. 2 is a top plan view thereof;

FIG. 3 is a left side elevational view thereof;

FIG. 4 is a right side elevational view thereof;

FIG. 5 is a front elevational view, the rear elevational view

being a mirror image thereof; and,

FIG. 6 is a bottom view thereof.
